UNITED STATES PATENT OFFICE.

EDWARD H. HEBERN, OF OAKLAND, CALIFORNIA.

CIPHER-WRITING MACHINE.

1,141,055.

Specification of Letters Patent. Patented May 25, 1915.

Application filed June 15, 1914. Serial No. 845,101.

To all whom it may concern:

Be it known that I, EDWARD H. HEBERN, a citizen of the United States, residing at Oakland, in the county of Alameda and State of California, have invented new and useful improvements in Cipher-Writing Machines, of which the following is a specification.

The object of the present invention is to provide means whereby a typewriting machine may, without changing the key board or the position of the type thereon, be used to write in cipher and also to decipher the cipher typewritten matter.

In the accompanying drawing, Figure 1 is a side view of a typewriting machine equipped with my invention; Fig. 2 is a perspective view of a swinging frame having a code strip removably carried thereon; Fig. 3 is a sectional view showing a spring latch; Fig. 4 is a front view of a modification of the invention; Fig. 5 is a sectional view; Fig. 6 is an enlarged broken plan view of a further modification of the invention; Fig. 7 is a broken front view thereof; Fig. 8 is a vertical section thereof; Fig. 9 is a perspective view of the same; Fig. 10 is a vertical section of a typewriting machine, showing a further modification; Figs. 11 and 12 are sections on the lines 11—11 12—12 of Fig. 10; Fig. 13 is a broken front view; Fig. 14 is a diagram of changeable codes; Fig. 15 is an enlarged diagrammatic view of a strip used therein.

Referring to the drawing, 1 indicates the key levers of a Blickensderfer typewriting machine. These key levers are all pivoted on the same shaft 2, and, as is well known, the effect of the depression of a key lever through the first portion of its downward movement is to rotate the printing cylinder up to the point at which the key lever arrives at a pivoted frame 3, and depresses said frame, the effect of which depression is to immediately lock the printing cylinder 4 against further rotation. The further depression of the key lever then causes the printing cylinder to be also depressed, so that the particular type which, by the rotation of the printing cylinder, has been brought into the proper position, descends upon the paper and makes an impression thereon. The selection of the type to make the impression is thus determined by the extent of rotation of the printing cylinder, and this again is determined by the extent

to which the key lever is depressed before it strikes the frame 3. This extent is determined by the depth of a projection on the under side of the key lever, which depth is different for the various key levers of the ordinary Blickensderfer typewriting machine. In my invention, however, these projections are all made of uniform depth, and the variation in the distance through which the several keys are depressed before the locking of the printing cylinder takes place is brought about by providing abutments of different heights, carried by the frame 3, with which abutments the several key levers contact on being depressed. It is evident that, if these abutments are formed on the frame, the same result is obtained as in the ordinary construction of the Blickensderfer typewriter. But by making these abutments movable on the frame, the depression of the same key lever will print a different character dependently upon the particular abutment which has been placed on the frame in such a position to be engaged by said key lever. These abutments can be made interchangeable in any manner desired, and indeed as an embodiment of my invention the downward projections, instead of the upwardly extending abutments, may be made interchangeable and effect the same result, but I herein show as preferred forms of my invention, different ways of making the abutments interchangeable.

Referring to Figs. 1 and 2 of the drawing, in the outer bar 7 of the swinging frame 3 is an undercut groove 8, in which is a metal strip 9 inserted through a properly shaped opening 10 formed in an end of the frame of the ordinary Blickensderfer machine, the upper edge of which strip is formed with two series of abutments 11, 12, the abutments of the two series alternating with each other, the abutments 11 being of such height as to arrest the printing cylinder at points which cause to be printed characters which correspond to those on the key lever, and thus producing ordinary writing, and the abutments 12 causing other characters to be printed, and thus producing cipher writing. These abutments are each of a width of one-half the distance at which the key levers are spaced from one another. To change from plain writing to cipher writing, the strip 9 is slid lengthwise through the width of an abutment by means of a handle 13 at an end, 110

and is retained in the proper position by means of a spring-actuated pin 14 having a conical point and slidably in bearings 16 carried by the frame 3, said pin entering one of two conical recesses 17 in the strip 9. By a sufficiently great longitudinal force applied to the strip 9, said strip may be moved so that the pin 14 is forced out of one of the recesses 17 against the force of the spring, and is then by the force of said spring caused to enter the other recess and hold the strip in the shifted position. The same detail of construction is clearly shown in Fig. 3.

In Figs. 4 and 5 of the drawings is illustrated a modification of the invention in which the abutments 11 for plain writing are dispensed with, and individually and independently changeable abutments 18 for cipher writing are employed in the bases of which are undercut grooves 19 which receive a dove-tailed portion 21 of strip 22 secured to the bar 7 in like manner as the strip 9, said abutments 18 being retained in place on said strip 22 by means of a handle 23 having a stem screwed into said strip.

Referring to Figs. 6 to 9 of the drawings the outer bar 7 of the swinging frame 3, is now made with its upper and lower edges beveled inwardly, and fits in an undercut groove 24 in a bar 26, the upper edge of which is formed with a series of integral vertical extensions or abutments 27, each of an average width in the longitudinal direction of the bar equal to one-half the distance at which the key levers are spaced from one another, and spaced from one another by recesses of the same width. These recesses are slightly dove-tailed in a direction transversely of the bar. The extensions 27 are used for writing ordinary writing with the typewriting keys, their heights corresponding with the depths of the projections on the key levers of the ordinary machine. The bar is at the front side reduced in thickness in its upper part, and in the top of the lower thicker portion of the bar is a longitudinal groove 28, in which are received downward extensions 29 from individually and independently changeable abutment bodies 31 which rest upon the top of the thicker portion of the bar, and have rearward extensions 32 which rest upon the top of the thinner portion of the bar. These extensions 32 having rearwardly and upwardly extending dove-tailed abutments 33 fitting in the dove-tailed intervals between the extensions 27. In order to prevent the rising of the abutments 33 from the bar 26 there is provided a long key 34, which fits in recesses formed partly in the bar 26 and partly in the abutment bodies 31. The key 34 at its end next the opening 10 is connected to a handle 36, which is also connected to a short plate 37, of the same cross-sectional form as the bar 7 of the frame 3, which plate fits snugly in the

dove-tailed groove 24 in line with the bar 7. To secure the plate 37 to the bar 26, there is provided a thumb screw 38, which is screwed into a hole in the bar 26, and through an open-ended slot 39 in the plate 37. When it is desired to change the code, that is, to change the position of the abutments 33, the whole bar 26 is removed from the machine, the thumb screw is unscrewed, so that the key 34 can be slid out of the recess, the abutment bodies are removed, and their positions changed, the parts are then replaced in position, the change of the code has been effected. The bar 26 is slid longitudinally and is retained in one of two positions, as before, to write ordinary or cipher writing by the pin 14 entering one of the recesses 17 in said bar.

Referring to Figs. 10 to 15 of the drawing, 41 indicates a bearing secured upon the bar 7, through which passes a tubular shaft 43, in which is a solid shaft 42. The shaft 42 extends beyond the shaft 43, and around the shaft 43 is a tubular shaft 44 and around the tubular shaft 44 is a tubular shaft 45. The shafts 42, 43, 44, 45 are rigidly secured respectively to cylinders 46, 47, 48, 49. Each cylinder is formed with a number, preferably ten, of grooves 51 parallel with its axis, and in said grooves are contained cipher strips 52, an enlarged view of one of which is shown in Fig. 15. These cipher strips are in general construction similar to the cipher strip 9, but they are shorter, those on the shafts 42 and 45 containing sixteen abutments, that is, eight for ordinary, and eight for cipher, writing, and those on the shafts 43, 44 containing only twelve abutments, six for ordinary and six for cipher writing. To shift the device for writing cipher writing instead of ordinary, or conversely, there is provided a lever 53, depending between the two cylinders 47 and 48, pivoted at 54, and formed near its pivot on opposite sides thereof with arms or projections 55. An arm 56, carrying a weight 57, swings on said pivot 54, and is adapted to rest on either of said projections 55, and, when so resting, presses the shafts and cylinders to the right or left as the case may be. Indicating marks 58 apprise the operator of the position of the weight, and therefore of the shafts and cylinders, and therefore whether the key levers in their depressions are adapted to be arrested by the abutments of the strips for ordinary or cipher writing. On the ends of the shafts 42, 43, 44, 45 are secured wheels 61, 62, 63, 64 each formed on the right-hand side with notches 66 and to which extend spring arms 67 secured to, and extending outwardly from, the corresponding shaft. Said wheels may be turned with reference to the shafts by removing the spring arms from the notches 66, said spring arms then entering recesses 68 in the left-

hand sides of the wheels to the right, and when said arms are withdrawn from notches the wheels can be turned to any extent desired, the spring arms being placed in other notches 66. A locking arm 69, pivoted on the wheel 64, can engage registering notches 70 in the peripheries of said wheels 61, 62, 63, 64 to lock them all together in any position to which they have been turned. 10 When so locked said shafts and the cylinders rotate in unison. With each operation of a key lever said cylinders are caused to rotate through the distance between adjacent strips by means of a pawl 71 pivoted at 72 on the frame of the typewriting machine, which, when a weight 73 on an arm 74 pivoted coaxially with the pawl is swung to the rear of the machine, engaging teeth of a ratchet wheel 76 secured to the wheel 20 64. When said weight is thrown to the front of the machine the teeth of said pawl are caused to be disengaged from said ratchet teeth. A wheel 77 is secured to the cylinder 49 and has rounded teeth 78, which are engaged in turn by a roller 79 carried by a pivoted horizontal arm 80, which roller, descending into the space between said teeth, serves to center the cylinder 49, so that the proper strips are in exactly the proper position to arrest the key levers. 30

In Fig. 14 I have illustrated diagrammatically the arrangement of the abutments on the strips of the cylinders for writing the different codes. All of the rows of strips of the several cylinders contain on the left-hand side abutments 81 which arrest the key levers in the position to produce ordinary writing, and these abutments are indicated by placing in corresponding positions in the upper line of Fig. 14 the letters of the universal key board, that is to say, upon depressing the key lever "Q," the letter "q" will be printed, because the first abutment of each strip of the cylinder 40 on the left is of such height as to arrest the printing cylinder at the point when the type "q" is immediately over the paper. And so on for the remaining letters of the universal key board. But if the shafts are moved to the left, by the swinging over of the weight in the manner before described, when, on the depression of this same key lever "Q" the key lever is arrested by an abutment 82 after a rotation of the printing cylinder of such extent that the type forming the letter "s" is immediately over the paper. 50

It will be observed referring to Fig. 15 that the letters "q" and "s" are pairs, or are in reciprocal arrangement to each other, for the letter "s" is printed by the depression of the key lever "q," and the letter "q" is obtained by the depression of the key lever "S." This same method is pursued with regard to all the letters, that is to say, they

are arranged in pairs, the letters of each pair being in reciprocal arrangement with each other as above explained. The advantage of this arrangement is that, to decipher a message, it is only necessary to write it on the same typewriter as, or a similar typewriter to, that on which it was written, when the original message will appear in ordinary writing. By the rise of the key lever the cylinders are rotated through one-tenth of a revolution, bringing the next succeeding strips into proper position to arrest the key levers. The depression of the key lever "Q" will now print, not the letter "s" but the letter "W," and it will be observed also that the depression of the key lever "w" will print the letter "q" so that in this strip as in all the strips the ciphering and deciphering are reciprocal. Thus it results that, upon the depression of each key lever, the code is entirely changed. The wheels 61, 62, 63, 64 have on their peripheries the numbers 0 to 9 corresponding with the different code strips carried by the cylinders on the shaft of said wheels. 50

A considerable saving is effected by my invention in the sending of telegraphic and cable messages, since numerals and signs, such as %, \$, which require to be written out in words in sending telegrams, may by my improvement be converted into signs for letters, thus reducing, for instance, six words to one. In deciphering it will at once be seen that if the message, when deciphered into letters would not make an intelligible word, then the key lever for figures must be depressed in order to obtain the correct meaning. 100

A further important advantage is that cable and telegraphic messages sent by code can be much simplified and abbreviated by numbering the different sentences in the code, and sending the numbers of the sentences in the message, first converting them, however, from numbers to letters. By my improved cipher device, for instance, sentences numbered 27-84-365 are transferred into RMANFAQLW and thus three sentences would go as one word. 110

I claim:—

1. The combination of typewriter key levers, type, operative connections therebetween and individually and independently changeable controlling devices for controlling said connections whereby the same type may be operated by different keys. 115

2. In a typewriting machine having a printing cylinder with type thereon, typewriter key levers, means actuated by the depression of said levers for rotating said cylinder, means actuated by the further depression of said levers for depressing said cylinder to produce an impression from type thereon, and means for arresting said levers to arrest the rotation of the cylinder, means 125

for varying the angles through which the key levers are depressed before being arrested, whereby the depression of the same lever arrests the cylinder at different points in its rotation.

3. In a typewriting machine having a printing cylinder with type thereon, typewriter key levers, means actuated by the depression of said levers for rotating said cylinder, means actuated by the further depression of said levers for depressing said cylinder to produce an impression from type thereon, and means for arresting said levers to arrest the rotation of the cylinder, means for changing the position of said arresting means, whereby the depression of the same lever arrests the cylinder at different points in its rotation.
4. In a typewriting machine having a printing cylinder having type thereon, typewriter key levers, means actuated by the depression of said levers for rotating said cylinder and means for depressing said cylinder to produce an impression from type thereon, removable abutments of different heights, and means for changing the position of said abutments, whereby the depression of the same lever arrests the cylinder at different points in its rotation.
5. In a typewriting machine having a printing cylinder having type thereon, typewriter key levers, means actuated by the depression of said levers for rotating said cylinder having type thereon, removable abutments of different heights, and means for changing the position of said abutments, whereby the depression of the same lever arrests the cylinder at different points in its rotation.

pression of said levers for rotating said cylinder and means for depressing said cylinder to produce an impression from type thereon, removable and interchangeable abutments of different heights, and means for changing the position of said abutments, whereby the depression of the same lever arrests the cylinder at different points in its rotation.

6. The combination of typewriter key levers, type, operative connections therebetween, a series of different interchangeable stationary controlling devices each adapted to control the operative connection between a key lever and a type, and means for rendering operative any one of said devices.

7. The combination of typewriter key levers, type, operative connections therebetween, a series of different interchangeable stationary controlling devices each adapted to control the operative connection between a key lever and a type, and means for rendering operative each of said devices in succession automatically with the operation of the typewriter machine.

In testimony whereof I have hereunto set my hand in the presence of two subscribing witnesses.

EDWARD H. HEBERN.
